The ornamental design for a numerically controlled drilling machine, as shown.

DESCRIPTION

FIG. 1 is a front elevational view of a numerically controlled drilling machine showing my new design;

FIG. 2 is a right side elevational view;

FIG. 3 is a left side elevational view;

FIG. 4 is a rear elevational view;

FIG. 5 is a top plan view;

FIG. 6 is a bottom plan view; and,

FIG. 7 is a perspective view thereof.

FIG. 7 has been drawn on a reduced scale with respect to FIGS. 1-6.

FIG. 1
FIG. 2FIG. 4

FIG. 3

FIG. 5

FIG. 6

FIG. 7
